UNITED STATES PATENT OFFICE.

WILLIAM H. DANIELS, OF CHICAGO, ILLINOIS.

BUILDING BLOCK OR BRICK.

No. 899,958.

Specification of Letters Patent. Patented Sept. 29, 1908.

Application filed July 2, 1907. Serial No. 381,825.

To all whom it may concern:

Be it known that I, WILLIAM H. DANIELS, a citizen of the United States, residing at Chicago, in the county of Cook and State of Illinois, have invented new and useful Improvements in Building-Blocks or Bricks, of which the following is a specification.

My invention has relation to a brick or building block for use in building chimneys or other structures, and it consists in the construction and arrangement of parts as will be hereinafter described and particularly pointed out in the claims.

In the accompanying drawings, Figure 1 is a sectional view of the upper portion of a chimney constructed of my improved bricks or blocks. Fig. 2 is a top plan view of one course thereof showing the interlocking bonding joints between the meeting ends of the several bricks or blocks in such course. Fig. 3 is a detail perspective view of one of my improved blocks.

In accordance with my invention, I provide a brick or block A which may be made of any suitable material, and may be of any suitable size. The block is constructed substantially of a rectangular parallelopipedon shape and having on opposite ends thereof vertical projections 3 of the same thickness as said block but of less width than the same, whereby a rabbeted end 4 is formed, said block being provided with a pair of endless grooves 1 and 1', each of said grooves extending in a vertical direction over said end portion and said rabbeted end and parallel to the edges of said block on the upper and lower faces of the same, the two transverse faces of said ends being each provided with one of said grooves.

In constructing a chimney, the above described block is used in conjunction with corner blocks B, as shown in Fig. 3. These blocks differ from the blocks A in that the end 6 is a plane surface instead of a rabbeted surface and the projection 5', similar to the projection 3, is formed on one side adjacent the end 6. These blocks are also provided with endless grooves which have portions 7

and 7' passing down the sides near the ends 6. When capping out a chimney constructed of my brick or blocks, as shown in Fig. 1, recesses such as at 5 may be filled with mortar or other plastic as at C. The extreme top of the chimney may also be formed of mortar or other plastic as at D.

Having described my invention what I claim and desire to secure by Letters Patent is:

1. A building block having the shape substantially of a rectangular parallelopipedon and having the vertical portions which are intended to abut against the vertical portions of other blocks formed with vertical projections of the same thickness as the block but of less width than the same, said block being provided with a pair of endless grooves, each of said grooves extending in a vertical direction over said vertical portions and parallel to the edges of the block on its upper and lower faces, the two transverse faces of said vertical portions being each provided with one of said grooves.

2. A corner block having the shape substantially of a rectangular parallelopipedon and having one end provided with a vertical projection of the same thickness as said block but of less width than the same, whereby a rabbeted end is formed, said block having the end portion of one side at the opposite end of the block provided with a vertical projection of the same thickness as the block but of less width than the same, the said block being provided with a pair of endless grooves, each of said grooves extending in a vertical direction over said end portion and said rabbeted end and parallel to the edges of the block on its upper and lower faces, the two transverse faces of said end portion and said rabbeted end being each provided with one of said grooves.

In testimony whereof, I affix my signature in presence of two witnesses.

WILLIAM H. DANIELS.
